Primary Examiner — Keli L Hill

(57) **CLAIM**

The ornamental design for a lid for baby wipe packaging, as shown and described.

DESCRIPTION

1. Lid for baby wipe packaging
1.17 is a right side elevation view shown in a closed configuration;
1.18 is a top front perspective view thereof;
1.19 is a left side elevation view thereof;
1.20 is a bottom plan view thereof;
1.21 is a front elevation view thereof;
1.22 is a top plan view thereof;
1.23 is a bottom perspective view thereof;
1.24 is a top front perspective view thereof;
1.25 is a left side elevation view thereof, shown in an open configuration;
1.26 is a front elevation view of **1.25**;
1.27 is a top plan view of **1.25**;
1.28 is a rear elevation view of **1.25**;
1.29 is a right side elevation view of **1.25**;
1.30 is a bottom plan view of **1.25**;
1.31 is a top front perspective view of **1.25**; and
1.32 is a bottom rear perspective view of **1.25**.
